DESIGN FOR A CHENILLE ROBE

Irving Weiser, New York, N. Y.

Application June 6, 1941, Serial No. 101,330

Term of patent 3½ years

To all whom it may concern:

Be it known that I, Irving Weiser, a citizen of the United States of America, residing in New York city, county of New York and State of New York, have invented a new, original, and ornamental Design for a Chenille Robe, of which the following is a specification, reference being had to the accompanying drawing, forming part thereof, wherein

Figure 1 is a front view of a chenille robe showing my new design.

Figure 2 is a rear view of the chenille robe shown in Figure 1, drawn on a smaller scale.

The characteristic feature of my design resides in the combination on the robe disclosed of the contrasting trimming around the sleeves, neckline, and down the front in association with the specific ornamentation around the bottom of the robe, as shown.

I claim:

The ornamental design for a chenille robe, substantially as shown and described.

IRVING WEISER.
